(57) **CLAIM**

The ornamental design for a fold-out, hand-held electronic game, as shown and described.

DESCRIPTION

FIG. 1 is an isometric view of a fold-out, hand-held electronic game, showing a first exemplary embodiment of our new design;

FIG. 2 is a top plan view thereof;

FIG. 3 is a front elevational view thereof;

FIG. 4 is a rear elevational view thereof;

FIG. 5 is a bottom plan view thereof;

FIG. 6 is a left elevational view thereof; and,

FIG. 7 is a right elevational view thereof.
